MACHINE FOR OPERATING IN ROCK, COAL,
AND THE LIKEEric Wilson Hurd, Sheffield, England, assignor
to Hardypick Limited, Sheffield, England, a corporation of Great Britain and Northern IrelandApplication January 22, 1951, Serial No. 207,218
In Great Britain July 5, 1949

6 Claims. (Cl. 255—51)

1

This invention relates to a machine for operating in rock, coal and the like.

When drilling a working face for setting blasting charges it is customary to mount the drill on a vertical pillar which is held in position by being wedged between the floor and ceiling. The drill is moved along the pillar to the required position until a row of shot holes has been drilled at the required spacing. The pillar is then moved to a new position. This means that to complete the drilling of the face the pillar has to be moved several times; moreover it is not always easy to mount the pillar so as to be able to drill shot holes near the side.

One of the objects of the present invention is to provide a machine which will enable all the required shot holes to be drilled without moving the machine.

In a coal or rock working machine according to the present invention a jib is adapted to carry a drill unit or drill holder and is turnable about a vertical axis, movable in a vertical plane, movable about its own axis and adapted to carry said drill unit or drill holder for pivotal movement about an axis normal to the axis of the jib. The jib may be mounted on a turntable which itself may be carried on a wheeled or track laying vehicle chassis.

Referring to the diagrammatic drawings filed herewith:

Fig. 1 is an elevation of one form of machine made according to this invention.

Fig. 2 is a plan, parts being omitted for clearness.

Fig. 3 is a sectional elevation of the jib.

Fig. 3a is an extension of Fig. 3.

Fig. 4 is a plan of same.

Fig. 4a is an extension of Fig. 4.

Fig. 5 is a sectional detail view, drawn to an enlarged scale, on the line V—V of Fig. 2.

In Figs. 1 to 4 inclusive, sheets 1, 2, 3 and 4, a self-propelled chassis 10, sheets 1 and 2, of the track laying type is provided with wheels 11, 12, at each side on which are carried tracks 13. Mounted on the chassis slightly towards the rear is a large toothed quadrant 14 horizontally disposed. Above the toothed quadrant and mounted for rotation over rollers 15 on the chassis is a turntable 16 the axis of which is vertical. The movement of the turntable through approximately 70° is effected by a turntable operating hand wheel 17 on a shaft 18 which is journalled in a pillar 19 mounted on the turntable, the shaft having at its lower end a pinion 20 in toothed engagement with the large horizontal quadrant

2

14. A stop (not shown) carried on the turntable is adapted to co-operate with limit stops (also not shown) provided on the chassis to limit the angular movement of the turntable.

5 The chassis is self-propelled by means of two electric motors 21 mounted on a platform 22 formed by an extension of the chassis at the rear thereof, the motors being coupled to and adapted to drive the shafts of the rear wheels 12 in well known manner through suitable reduction gears, the primary drive being by chain enclosed in the chain case 23. Steering is effected by dual control levers (not shown) in the known manner operating either or both of the motors.

10 Two upstanding plates 24, Figs. 1 and 2, sheets 1 and 2, welded to the top of the turntable 16 and located for the most part to the rear of the centre and extending rearwardly, constitute brackets between which is mounted a jib cradle 25 on horizontal trunnions 26, Figs. 1, 2 and 3, sheets 1, 2 and 3, provided thereon and located at one end thereof, the journals 27 for which are provided in the plates 24 close to the turntable operating hand wheel 17. Movement of the cradle 25 in a vertical plane between the plates 24 is controlled

15 by hydraulic jacks 28, Fig. 1, sheet 1, the cylinders of which are pivotally connected at 29 to the rear of the turntables 16 whilst the piston rods 30 of the jacks are pivotally connected at 31 to an elevating bracket 32 secured to the jib cradle 25, the pump for the jacks being enclosed within a housing 33, Fig. 2, and being actuated by a hand lever 34. The housing 33 is fixed to a central seat 35 for an operator of the machine, which

20 seat also serves as a tool-box and is located on and situated at the rear of the turntable 16 conveniently close to the turntable operating hand wheel 17. The central box seat 35 also serves as a convenient mounting for a switch box 35a for electrical switch gear one element of which feeds the chassis propelling motor switch box 35b through electrical lead 35c, the current being supplied through a feed cable 36 led into the switch box 35a.

25 Mounted and journalled in the jib cradle 25 is a hollow jib shaft 37, Figs. 3 and 4, provided with a worm wheel 38 whilst mounted on the outside of the jib cradle in suitable bearings and arranged tangentially to the worm wheel and in mesh therewith, is a worm 39 on one end of which is mounted a jib rolling hand wheel 40 so that the jib shaft may be rotated or rolled slowly on its axis through 180° from zero in either direction to

30 the desired angular position within the jib cradle

35 45 50 55

25 by the operation of the jib rolling hand wheel 40.

Carried on the forward end of the jib shaft 37 which projects beyond the jib cradle is a double boom jib 41, Figs. 1, 2, 3 and 4. The forward free ends of the booms are provided with journals 42 in which is pivotally mounted on trunnions 43, a self feeding electrically driven self contained drill unit 44 supplied by current from the switch box 35a, Fig. 2, by electrical lead 44a and with feed 10 and retraction control lever 45 and Bowden wire control 46 mounted on the jib cradle mounting brackets 24. Pivotal movement of the drill unit 44 about the mounting trunnions 43 is controlled by a forked link rod 47, Figs. 3 and 4, divided 15 intermediate of its ends and embodying a stiff spring buffer 48, the forked end of the link rod being bifurcated and pivotally coupled to the housing of the drill at a point spaced from the drill mounting trunnions whilst the other end is pivotally coupled at 49 to a hollow internally threaded rod 50 which is slidably mounted in the hollow jib shaft 31. The rod 50 is caused to be projected or withdrawn by turning a drill angling cranked hand lever 51 mounted at the rear end of the jib cradle 25, said hand lever being carried on a threaded shaft 52 which enters and engages the internally threaded rod 50. The movement of the bifurcated link rod 47 thus gives the drill unit a pivotal movement on its own mounting trunnions 43 within the journals 42, which movement can be locked in any desired angular position of the drill unit.

The function of the buffer spring 48, shown in Figs. 3 and 4, is embodied in the drill unit angling control to allow the drill unit 44 to tilt on its pivots to relieve any strain which would otherwise fall on the drill tool or the drill shaft.

In operation, the angle at which the drill unit 44 is presented can be varied by rolling the double boom jib 41 in the jib cradle 25 through the medium of the jib rolling hand wheel 40 and/or by pivoting the drill unit in the end of the jib by means of the drill angling hand lever 51. The drill unit may be directed to the desired point on raising or lowering the jib by the actuation of the pump hand lever 34 which works the pump for the jacks 28 and/or by swivelling the turntable 16 by turning the turntable actuating hand wheel 17.

By arranging that the drilling tool 53 operates on an axis which intersects the axis of the drill mounting trunnions 43, the thrust from drilling is taken by said trunnions and their journals 42 in the jib. Further by arranging said trunnions and the drilling tool near a boundary of the body of the drill unit said drilling tool operates with very small loss of headroom.

It will therefore be seen from the chain lines in plan view, Fig. 2, how the drill unit 44 can be disposed on its side by swinging the jib 41 to right or left and rolling it on its axis through 90° at either side from zero, thereby enabling the drill unit to operate substantially at the extreme sides of the working face 54 of the coal. Similarly, by suitably lowering the jib 41 and rolling it on its axis through 180° from zero, the drill unit will be disposed in an inverted position to operate substantially at any point in the lowermost part of the working face 54.

It is to be noted that all controls are arranged within easy reach of the operative when the latter is seated on the housing 33.

Suitable lamps 55 are provided on the machine

to enable it to be operated below ground and all electrical equipment is enclosed and switch gear is housed in flame proof boxes to comply with mine regulations.

Where it is required that the turntable shall be capable of being locked in any desired drilling position, a friction type clutch arrangement is provided between the pillar 19 and shaft 18, and carried by a flanged sleeve 60 non-rotatably mounted on the pillar 19 adjacent the upper end thereof and supported by an integral flange 61 of the pillar. Disposed around the sleeve 60 between and in contact with a pair of friction rings 62, 63 thereon is a steel ring 64, the friction ring 62 engaging the flange 65 of the sleeve and the friction ring 63 engaging a steel ring 66 which is slidably keyed to the sleeve 60 and supported by a locking ring 67 having screw-threaded engagement with the sleeve 60, the flange 61 of the pillar 19 serving as a stop for preventing the locking ring 67 from becoming completely unscrewed from the sleeve 60. For rotating the locking ring 67, at least one arm 68 is pivotally slung therefrom.

The arrangement is such that when the locking ring 67 is slackened off the ring 64 is free to rotate around the sleeve 60 but when said locking ring is tightened against the ring 66, the ring 64 is held against rotation through being clamped to the friction rings 62, 63.

The ring 64 is provided with an aperture 69, adjacent its periphery, which is normally engaged by the lower end of a spring-urged detent 70 carried in the hand wheel 17 by a slidable pin 71. The detent 70 is normally urged into engagement with the aperture 69 of the ring 64 by means of a coiled spring 72 bearing against a shoulder 73 on the detent 70 and the end wall 74 of a socket 75 in the hand wheel 17. The pin 71 is provided with a head 76.

When it is desired to rotate the turntable 16, the locking ring 67 is rotated and slackened by manipulating the arm 68 until the clamping pressure of the friction rings 62 and 63 upon the ring 64 is relieved, and the hand wheel 17 rotated until the desired angular movement of the turntable is attained. The locking ring 67 can then be tightened to lock the ring 64 to the sleeve 60 and so to the pillar 19, to lock the turntable in a particular drilling position. If a temporary alteration in the angular position of the turntable becomes necessary, it being required subsequently to return it to said angular position, the detent 70 is raised, out of engagement with the aperture 69 by pulling on the pin 71 against the spring 72, when riding over the ring 64. To reset the turntable in the original angular position, it is only necessary to rotate the handwheel 17 until the detent 70 drops into its aperture 69 in the ring 64.

It is to be understood that instead of the various mechanisms being brought into operation by manually controlled means as hereinbefore described and shown, they may be arranged to be power operated and brought into operation by electrical control means, such as for example, by push-button switches.

A pivoted jib support and associated clamp (not shown) may be provided on the turntable so that when the machine is not in use or whilst it is being transported, the jib support may be swung up by hand into position beneath the jib, the jib lowered thereinto and the clamp secured so that the jib is firmly held and its weight taken by said support instead of by the jack.

What I claim and desire to secure by Letters Patent is:

1. In a coal or rock working machine the combination of a turntable turnable about a vertical axis, means for adjusting said turntable, a jib carrying cradle carried on said turntable and pivotally mounted thereon at one end for movement in a vertical plane, means for adjusting said jib carrying cradle in a vertical plane, a hollow shaft journalled in said jib carrying cradle for rotation about its own axis and movable with said jib carrying cradle, means for adjusting said hollow shaft about its own axis, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, and drill unit angle adjusting means comprising a rod member mounted in said jib carrying cradle for lateral movement in relation thereto together with associated lateral motion means, and a second rod member pivotally secured to the upper end of the latter and pivotally secured to said drill unit for rotational movement of the latter about its pivoting axis.

2. In a coal or rock working machine the combination of a turntable turnable about a vertical axis, means for adjusting said turntable, a jib carrying cradle carried on said turntable and pivotally mounted thereon at one end for movement in a vertical plane, means for adjusting said jib carrying cradle in a vertical plane, a hollow shaft journalled in said jib carrying cradle for rotation about its own axis and movable with said jib carrying cradle, means for adjusting said hollow shaft about its own axis, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, and drill unit angle adjusting means comprising a rod member mounted in said jib carrying cradle for lateral movement in relation thereto together with associated lateral motion means and a second rod member pivotally and flexibly secured to the upper end of the latter and pivotally secured to said drill unit for rotational movement of the latter about its pivoting axis.

3. In a coal or rock working machine the combination of a transportable carriage having mounted thereon a turntable turnable about a vertical axis, means for adjusting said turntable, a jib carrying cradle carried on said turntable and pivotally mounted thereon at one end for movement in a vertical plane, means for adjusting said jib carrying cradle in a vertical plane, a hollow shaft journalled in said jib carrying cradle for rotation about its own axis and movable with said jib carrying cradle, means for adjusting said hollow shaft about its own axis, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, and drill unit angle adjusting means comprising a rod member mounted in said jib carrying cradle for lateral

movement in relation thereto together with associated lateral motion means and a second rod member pivotally secured to the upper end of the latter and pivotally secured to said drill unit for rotational movement of the latter about its pivoting axis.

4. In a coal or rock working machine the combination of a transportable carriage having mounted thereon, a turntable turnable about a vertical axis, means for adjusting said turntable, a jib carrying cradle carried on said turntable and pivotally mounted thereon at one end for movement in a vertical plane, means for adjusting said jib carrying cradle in a vertical plane, a hollow shaft journalled in said jib carrying cradle for rotation about its own axis and movable with said jib carrying cradle, means for adjusting said hollow shaft about its own axis, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, self feed and self retracting means associated with said drill unit, and drill unit angle adjusting means comprising a rod member mounted in said jib carrying cradle for lateral movement in relation thereto together with associated lateral motion means and a second rod member pivotally secured to the upper end of the latter and pivotally secured to said drill unit for rotational movement of the latter about its pivoting axis.

5. In a coal or rock working machine the combination of a tracklaying vehicle having mounted thereon a turntable turnable about a vertical axis, means for adjusting said turntable, a jib carrying cradle carried on said turntable and pivotally mounted thereon at one end for movement in a vertical plane, jib elevating hydraulic jack means for adjusting said jib carrying cradle in a vertical plane, a hollow shaft journalled in said jib carrying cradle for rotation about its own axis and movable with said jib carrying cradle, means for adjusting said hollow shaft about its own axis comprising a worm and worm-wheel mechanism associated between said hollow shaft and said jib carrying cradle, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, self feed and self retracting means associated with said drill unit, and drill unit angle adjusting means comprising a rod member mounted in said jib carrying cradle for lateral movement in relation thereto together with associated lateral motion means and a second rod member pivotally and flexibly secured to the upper end of the latter and pivotally secured to said drill unit for rotational movement of the latter about its pivoting axis.

6. In a coal or rock working machine the combination of a tracklaying vehicle having mounted thereon a turntable turnable about a vertical axis, means for adjusting said turntable, a jib carrying cradle carried on said turntable and pivotally mounted thereon at one end for movement in a vertical plane, jib elevating hydraulic jack means for adjusting said jib carrying cradle in a vertical plane, a hollow shaft journalled in said jib carrying cradle for rotation about its own

axis and movable with said jib carrying cradle, means for adjusting said hollow shaft about its own axis comprising a worm and worm-wheel mechanism associated between said hollow shaft and said jib carrying cradle, a jib member which is bifurcated at its outer end, said jib member being co-axial with said hollow shaft and secured thereto at its inner end, a drill unit pivotally cradled in the bifurcated end of said jib member for movement about an axis normal to the axis of the jib member said pivot intersecting the axis of the drill, self feed and self retracting means associated with said drill unit, and drill unit angle adjusting means comprising a rod member mounted in said jib carrying cradle for lateral movement in relation thereto together with associated lateral motion means, a second rod member pivotally and flexibly secured to the

upper end of the latter and pivotally secured to said drill unit for rotational movement of the latter about its pivoting axis and means associated with the turntable adjusting means for locking said turntable in any adjusted position.
